UNITED STATES PATENT OFFICE.

VICTOR E. EDWARDS, OF WORCESTER, MASSACHUSETTS, ASSIGNOR TO THE MORGAN CONSTRUCTION COMPANY, OF WORCESTER, MASSACHUSETTS, A CORPORATION OF MASSACHUSETTS.

ROLLING-MILL.

SPECIFICATION forming part of Letters Patent No. 729,559, dated June 2, 1903.

Application filed December 23, 1898. Serial No. 700,186. (No model.)

To all whom it may concern:

Be it known that I, VICTOR E. EDWARDS, a citizen of the United States, residing at Worcester, in the county of Worcester and 5 Commonwealth of Massachusetts, have invented a new and useful Improvement in Rolling-Mills, of which the following is a specification accompanied by drawings forming a part of the same, and in which—

- 10 Figure 1 is a plan view of a rolling-mill embodying my invention. Fig. 2 is a front elevation of that portion of the rolling-mill known as the "finishing-mill," comprising two sets of two-high rolls with intermediate 15 connecting mechanism comprising a pinion-housing and a train of gearing. Fig. 3 is a vertical central sectional view of the pinion-housing and gearing. Fig. 4 is an end view of the same. Fig. 5 is an end view of the pinion-housing with the pinions and journal-bearings removed. Fig. 6 is a top view of a 20 finishing-mill having a greater number of pairs of rolls, with a rod passing successively through the several pairs of rolls. Fig. 7 is 25 a plan view of a rolling-mill representing more in detail the method of carrying my invention into practice and comprises an arrangement of two-high stands of rolls similar to that shown in diagrammatic view in Fig. 6 30 by one of the trains N or N', and I have added to Fig. 7 devices for conducting a rod or bar alternately from a pair of rolls running in one direction to a pair of rolls running in the opposite direction. Fig. 8 is a front elevation 35 of the rolls shown in plan view in Fig. 7. Fig. 9 is a sectional view on line 9 9, Fig. 7, and Fig. 10 is a sectional view on line 10 10, Fig. 7.

Similar reference letters and figures refer to 40 similar parts in the different views.

My invention relates to that portion of a rolling-mill known as the "finishing-mill;" and it consists in the arrangement of two or more trains of rolls of different diameters with parallel axes, but placed out of alignment with each other, whereby the metal to be rolled is conducted from one to the other in a series of intervening loops, and each of the trains can be conveniently driven from the same

source of power at different speeds corresponding to the reduction of metal in the several trains of rolls, and it further consists in the arrangement of the rolls in each train with intermediate connecting mechanism and in the novel features of arrangement and construction, as hereinafter described, and set forth in the annexed claims.

Referring to the drawings, A denotes a train of rolls forming what is known as a "continuous rolling-mill," by which a heated billet is taken from the furnace, reduced in cross-section, and delivered from the last pair of rolls through a tube B or suitable conductor to a point slightly beyond the rolls C of the finishing-mill, and from the end of the tube B the rod a is conducted in a semicircular loop to the rolls C or the first pair of rolls in the first series of rolls constituting the finishing-mill.

The finishing-mill comprises in the present instance two trains of rolls D and E. The train D comprises two pairs of rolls C and F and the train E comprises two pairs of rolls G and H.

The pair of rolls C consists of the upper roll c and the lower roll c' and the pair of rolls F consists of the upper roll f and lower roll f', comprising the train D. The pair of rolls G similarly consists of an upper roll and lower roll and the pair H also consists of an upper roll and lower roll, comprising the second train E. The rolls in the first train D are driven at a uniform angular velocity by means of the belt-pulleys I and J and belt J' and the second train of rolls E are driven at a uniform but a higher angular velocity by means of the pulleys I and J² and belt J³.

The pairs of rolls F and H are larger in diameter than their connected pairs C and G, and therefore have a greater circumferential speed. For example, the rolls in the pairs C and G are nine inches in diameter and the rolls in the pairs F and H are twelve inches in diameter. Power is imparted to the rolls in the first train D by means of a shaft K, carrying the belt-pulley J and coupled with the shaft of the upper roll c. Intermediate between the pairs of rolls C and F is a pin-

ion-housing L, containing the pinion-shafts L', L², and L³, placed one above the other, with the shafts L' and L² connected by nine-inch pinions h and h' and the shafts L² and L³ connected by the twelve-inch pinions i, i', i², and i³.

The lower pinion-shaft L' is in alinement with the shaft of the lower roll c', the upper pinion-shaft L³ is in alinement with the shaft of the upper roll f, and the middle pinion-shaft L² is in alinement with the shafts of the upper roll c and lower roll f' on opposite sides of the pinion-housing. The pinion-housing L consists of a pair of upright posts j and j' upon each side of the housing, inclosing the vertical slot j² sufficiently wide to receive the journals of the pinion-shafts. The vertical posts j j' are provided on opposite sides of the slot j² with recesses j³, adapted to receive the annular journal-bearings j⁴ of the pinion-shafts.

Each of the pinion-shafts is journaled in annular journal-bearings j⁴, provided with ears j⁵, which overlap the posts j j' and are attached thereto by bolts j⁶. The pinion-housing is stiffened by the bolts k, connecting the upper ends of the vertical posts j j'.

The pinions are readily removed from their housing by withdrawing the annular journal-boxes from the ends of the pinion-shafts, removing the bolts k, and lifting the pinion-shafts out of the vertical slots j². The specific construction of the pinion-housing, as both described and illustrated in the drawings, is not herein claimed, said improvement in the pinion-housing forming the subject-matter of a copending divisional application, filed February 4, 1903, Serial No. 141,818.

The rod a is conducted successively through the pairs of rolls C, F, G, and H, forming semicircular loops between each two pairs of rolls, which allow for any difference in the speed of the rod as it passes through the several pairs of rolls. As the rod passes to each pair of rolls C, F, G, and H successively, its length is increased by the reduction of the rod in cross-section, and this increase in length is taken up between the rolls C and F and the rolls G and H by the increased circumferential speed due to the greater diameter of the rolls F and H, and the increase in the length of the rod between the rolls F and G is taken up by the increased angular velocity of the driving-shaft K', by which the rolls G and H are driven.

I have described a finishing-mill comprising two trains of rolls independently driven at different velocities and used in connection with the train of a continuous rolling-mill for the purpose of finishing the rod after its reduction by the continuous mill; but I do not confine myself to the employment of the above-described finishing-mill in connection with the continuous mill, as it is obvious that the metal may be taken directly from a furnace and passed through the rolls.

of the finishing-mill, neither do I confine myself to the use of a single pair of rolls upon opposite sides of the pinion-housing, as the train may be increased by the employment of two or more pairs of rolls upon each side of the pinion-housing and the rod conducted in a circuit from one side to the other of the pinion-housing until it has passed successively through each pair of rolls in the train, when it may be conducted to a second similar train, as represented in Fig. 6, where I have shown two trains of rolls N and N', each comprising six pairs of rolls, with three pairs, 1, 3, and 5, running in one direction, and three pairs, 2, 4, and 6, in the opposite direction, with the rolls running in one direction connected with those running in the opposite direction by a stand of three-high pinions, as already described, and journaled in pinion-housings M M', as shown in Figs. 2, 3, and 4. The rod b is passed between the pair of rolls 1 and conducted in a semicircular loop 7 to the opposite side of the pinion-housing and passed between the pair of rolls 2. From the rolls 2 it is conducted in a semicircular loop 8 to the pair of rolls 3, and in similar loops 9, 10, and 11 successively between the pairs of rolls 4, 5, and 6, the semicircular loops 7, 8, 9, 10, and 11 forming approximately a spiral between the points of initial entrance and final exit of the rod b from the train of rolls. As the rod leaves the roll 6 it may be cut up or, if desired, conducted to the train N' and the operation repeated, as indicated by the spiral line 12.

The above-described arrangement of rolls is especially adapted to the continuous rolling of a rod in a circuit as the line of motion of the rod. As it enters, each pair of rolls is parallel with its line of motion as it leaves the preceding pair of rolls, making the loops between the passes substantially semicircular with the parallel lines of motion as the rod enters and leaves the mill tangential to the semicircular loop, whose curvature remains substantially constant, thereby preventing the trickling or irregular bending of the heated rod, and the entire process is completed by the use of stands of two-high rolls only.

The arrangements of the rolls shown in the trains N and N' are in the present instance duplicates; but the relative size or speed of the rolls can be varied as desired or one of the trains can be omitted. The arrangement of the several pairs of rolls in the train N for the formation of the semicircular loops on opposite sides of the rolls allows all the pairs of rolls to be operative. Each pair of rolls is provided with an operative pass adapted to act in the continued reduction of the rod, and the several consecutive passes are arranged in alternation on opposite sides of a center line at right angles to the axes of the rolls and between the series of rolls relatively to the consecutive passes of the rolls, which

is, so far as I am aware, novel and possesses many advantages.

It requires two-high housings only for the rolls and the mechanism for communicating motion to the several pairs of rolls on each side of the pinion-housing. It affords a clear space on opposite sides of the pinion-housing and in front of the rolls.

Figs. 7, 8, 9, and 10 are intended to illustrate more clearly the arrangement of a train of rolls, such as that shown at N or N' in Fig. 6, with the train divided into two sets or series N² and N³, with the rolls in the series N² running in one direction and the rolls in the series N³ running in the opposite direction, with the consecutive passes or grooves in the rolls alternating from one series to the other or from a set of rolls running in one direction to a set running in the opposite direction. Power is imparted directly to the series of rolls N² from an engine by means of the belt-pulley P, and power is imparted to the second series of rolls N³ by a three-high pinion-housing Q, thereby causing the rolls in the series N³ to be rotated in the opposite direction in the series of rolls N². In order to show more clearly the movement of a rod or bar from one pass to the next consecutive pass in the rolls, I have shown the passes in the several pairs of rolls as connected by "repeaters" O, which are of the usual form of construction employed in rolling-mills, and consist of curved guides for the rod or bar, substantially like those illustrated in Fig. 1 of the drawings of the United States patent granted to S. V. Huber February 25, 1896, No. 555,375. Said repeaters O, however, form no part of my present invention and are shown in Figs. 7 to 10 in order to indicate more clearly the arrangement of consecutive passes, by which I am enabled to avoid the use of three-high stands of rolls in a finishing-mill and also the necessity of transmitting power from one stand of rolls to another stand across an intervening stand of rolls by means of a shaft journaled in the intervening stand and passing either above or below the rolls in said intervening stand. I thereby secure a great advantage in rolling-mill construction, especially in that portion known as the "finishing-mill," as it enables the entire reduction of the rod to be accomplished by a series of pairs of rolls held in two-high roll-housing, having a space both above and below the pairs of rolls entirely free for roll-adjusting and roll-supporting devices, whereby a rigid and unyielding structure is secured, which is essential to accuracy of dimension in the finished product. Such stands of two-high rolls are at present employed in finishing-mills as the last pair of rolls by which the final reduction is given to the rod or bar and its dimensions determined, and from the characteristic features of their construction they are usually

heads." By my improvement in the construction of finishing-mills all the stands of rolls are bull-heads, and consequently each reduction of the rod is determined and carried into practice with exactness and accuracy.

What I claim as my invention, and desire to secure by Letters Patent, is—

1. In a rolling-mill, the combination of a train of two pairs of rolls, each of said pairs of rolls having different diameters, pinions by which said pairs of rolls are connected, the rolls of each pair being connected by pinions of different diameters respectively, and with two pinions, one for each pair carried on the same shaft, substantially as described. 70 80

2. In a rolling-mill, the combination of a train of rolls comprising at least two pairs of rolls of different diameters, with the upper and lower rolls of each pair of the same diameter, pinions by which the rolls of each pair are connected, the rolls of each pair being connected by pinions of different diameters respectively, and means for rotating both pairs of rolls at the same angular velocity. 85

3. The combination of two pairs of rolls G and F having different diameters, housings supporting each of said pairs of rolls, an intermediate housing, three pinion-shafts journaled in said intermediate housings, pinions carried by the upper and lower of said pinion-shafts, two pinions carried by the middle of said pinion-shafts engaging the pinions of the upper and lower pinion-shafts respectively, the pinions of the upper and lower shafts and their engaging pinions being of different diameters, substantially as described. 90 95 100

4. A rolling-mill consisting of three or more pairs of operative rolls with their axes substantially parallel with at least two or more pairs of said operative rolls having consecutive passes placed in alternation on opposite sides of the third pair of operative rolls, with each of said consecutive passes formed in independent pairs of rolls, whereby each pass is capable of independent adjustment, substantially as described. 105 110

5. A rolling-mill consisting of a series of three or more pairs of rolls provided with consecutive passes for the continuous reduction of a rod and having the several series of rolls arranged to bring the consecutive passes in alternation on opposite sides of an operative pair of rolls constituting one end of said series, with each of said consecutive passes formed in independent pairs of rolls, whereby each pass is capable of independent adjustment, substantially as described. 115 120

6. A rolling-mill consisting of three or more two-high stands of rolls, each of said stands containing a pair of rolls having a pass for the reduction of a rod, said pairs of rolls being arranged in two trains or series with the rolls of one train running in the opposite direction to the rolls in the other train or 125 130

series, said rolls having their consecutive passes alternating from one train or series to the other, whereby the rod is taken through a pass in one train or series, then through a 5 pass in the other train or series, then back through the next consecutive pass in the first train or series, and so on through the sev-

eral consecutive passes, substantially as described.

Dated this 15th day of December, 1898.
VICTOR E. EDWARDS.
